UNITED STATES PATENT OFFICE.

GEORGE W. T. HARLEY, OF FREDERICK, MARYLAND.

DESIGN FOR THE ORNAMENTATION OF TEXTILE FABRICS.

SPECIFICATION forming part of Design No. 18,933, dated February 19, 1889.
Application filed January 17, 1889. Serial No. 296,653. Term of patent 14 years.

To all whom it may concern:

Be it known that I, GEORGE W. T. HARLEY, a citizen of the United States, residing at Frederick, in the county of Frederick and State of Maryland, have invented and produced a new and original Design for the Ornamentation of Fabrics for Gentlemen's Wear, of which the following is a specification, reference being had to the annexed drawing.

The figure is a plan view of a portion of a bolt or roll of cloth, showing my new and original design for striped ornamentation of cloths, the ornamentation consisting of lines or stripes 5 $b b'$, which start from opposite points on the selvage edges $a a'$ of the cloth and converge toward each other in corresponding lines of convergence, said stripes extending over the face of corresponding opposite portions, $B B'$, of the cloth and meeting on a center longitudinal line or fold, a^2 , between said opposite portions $B B'$ of the cloth or fabric.

Whatever may be the color and texture of the cloth for garments for gentlemen, I have designed for its outer or wearing surface

stripes or lines $b b'$, (whether in colors or otherwise and whether of greater or less width,) which commence at corresponding points on the selvage edges $a a'$ and converge and meet, forming an angle at f on the longitudinal 30 fold or center line, a^2 , of the cloth, thereby presenting a pleasing, uniform, ornamental appearance not heretofore shown in striped goods.

I claim—

The design for the ornamentation of textile fabrics herein shown and described, the same comprising lines or stripes $b b'$, which start from opposite points on the selvage edges of the cloth and converge toward each other in 40 corresponding lines of convergence, such lines or stripes extending over the face of corresponding opposite portions $B B'$ of the cloth and meeting on a longitudinal center line or fold, a^2 , between said opposite portions $B B'$ 45 of the cloth or fabric, as set forth.

GEORGE W. T. HARLEY.
